UNITED STATES PATENT OFFICE.

LOUIS VAN GALE, OF ASTORIA, NEW YORK.

AUTOMOBILE SIGNAL DEVICE.

Application filed January 24, 1923. Serial No. 614,529.

This invention relates to auto signals, so-called, which are signal devices for use on automobiles or for like purposes. In particular, this invention has for its object the 5 simplification of construction, cheapening construction, and other advantages which will hereinafter appear. The construction particularly involves the casing of such signals or signal boxes, and especially sections 10 of signal boxes such as those shown and described in my co-pending application for United States Letters Patent Serial No. 587, 693, filed September 12, 1922.

Among the particular objects are the construction of sections for signal boxes which will provide in a most convenient and simple way for the reception of the glass or transparent side pieces which are transparencies and may be of various forms, and also the 20 economy of stamping and pressing the sides of the box and the assembling of the sides or sections, in order to economize in the operations and to therefore simplify the process of construction and at the same time provide 25 a thoroughly durable and substantial article of this character.

While the inventions may be embodied in various ways, I have shown certain particular embodiments in the accompanying drawings, in which:

Fig. 1 is a rear elevation of a signal box.

Fig. 2 is a side elevation of Fig. 1.

Fig. 3 is a vertical longitudinal section of a separately-made section assemblable as 35 an element of the box.

Fig. 4 is a cross-section on an enlarged scale, on the line 4—4 of Fig. 3.

Fig. 5 is a bottom view of the sectional element as shown in Fig. 3.

40 The signal box comprises the base 1 with an upright side 2 and a hinged side 3 and a top 4. Between the base 1 and the top are three elements constituting separately made and readily assemblable sections 5—5.

45 The separate element 5 is made of two pieces of sheet metal 6, 7, each one of which is bent U-shape with one short side leg 8 and one long side leg 9, with the wall between the same cut out to form a window 50 permitting a clear view of a glass or other suitable transparency 11. This is preferably of glass with the lettering—Stop or Right or Left—so arranged that an electric light 12 on the inside of the section will suitably 55 display the visibility of these words, as provided in signals and as more specifically set

forth in my co-pending application. As to the nature of this transparency, this may be subject to suitable modifications.

The legs 8, 9 of sections 6, 7, on this box 60 element 5, each terminate in a crimped edge so that the edge of one engages the edge of the juxtaposed section to form lock seams 13—13. Thus the sections 6 and 7 may be made of identical stampings, and in view of 65 their shape permit their manufacture with simple operations and with great economy. Thus the crimped edges for the lock joints may be made in the edge of the other material, and as soon as it is bent up the reversed 70 sections may be slid together longitudinally so that the lock joints engage, and the box so formed is put over a mandrel and the joints pressed, thereby completing a solid structure.

In the top and bottom of these sections, at suitable time in the manufacture, ears 14—14 are pressed out of what becomes the top and bottom of the sectional element, which ears are bent down, as shown at 14^a, 80 14^a, when the glass 11 is inserted in the completed section, and thereby hold the glass firmly in position.

It will thus be seen that the structure herein specifically described affords means 85 for very economically producing sectional elements for a signal box, such, for example, as shown in Figs. 1 and 2, and to produce structurally stiff, lightweight and durable parts of such articles or similar structures.

90 In attempting to fold metal by pressing into a box shape, expensive dies are involved when more than two folds are made at substantially right angles, and by the process and structure herein described such expense 95 is greatly minimized by making the rectangular box out of two separate parts, each one of which requires only the turning up of two sides. Whether these boxes or sectional elements are square or rectangular, that is

100 with unequal sides, the advantages of construction are equally involved. By this construction greatest facility is also afforded for aperturing one side of the built-up section so as to provide the desired opening 105 to be covered by a glass or suitable transparency, but also provides the means for holding the glass securely in position, with the minimum operations and therefore the minimum cost of dies, in the forming of the 110 structure. The section 6 and the section 7 of the box, it will be noted, are identical,

when formed, and they are simply reversed in position for assembly, so that one set of dies is sufficient to make both parts of the box, and this is particularly applicable to the signal device involved, because the glass or transparency opening is both at the front of the box and the rear of the box, or both front and rear of each section, and consequently the symmetrical top and bottom are in combination with the symmetrical front and rear, in every detail of construction.

While these improved sectional boxes as developed are essentially advantageous for use in connection with the signal boxes as herein shown, and as more fully described in my co-pending application, the inventions may be found applicable for other purposes both for economy of construction and advantages in other respects.

Various modifications may be made without departing from the spirit of this invention, but what I claim and desire to secure by Letters Patent is:

1. In combination in an automobile signal box, a sectional element comprising two identical integral stamped metal sections, one forming a front side and part of top and bottom of the casing, and the other forming the rear side and part of bottom and top, the front and rear sides being symmetrical, a sign panel in the front side and a sign panel in the rear side and means to support a transparency adjacent each panel, symmetrical interconnecting seams on the interior of the top and bottom sides, and a source of light enclosed in said element.

2. A sectional element for an automobile signal case, comprising a rectangular open-ended stamped metal box adapted to enclose a source of light, two identically shaped stamped sheet metal parts, crimped edges on each of the parts forming interlocking joints one at the top side and the other at the bottom of the box with the joint projecting on the interior surface and providing flush top

and bottom flat outside surfaces, a sign panel in the front of one part and a sign panel in the rear of the other part, and means for holding a transparency sign in cooperative relation with each of said panels.

3. In an automobile signal case a plurality of sectional elements each consisting of a rectangular shaped box adapted to register one on the top of the other, each sectional element having flush top and bottom flat surfaces, said boxes each comprising two flat-sided stamped metal parts each of identical cross-section with interengaging joints inwardly projecting on each section, and means in said signal box for locking said plurality of elements together in fixed engagement.

4. An automobile signal case comprising a plurality of sectional elements each consisting of a stamped metal box of rectangular cross-section enclosing a source of light, each box element having a flush top and bottom surface and flat-sided front and rear faces and a sign panel in the front and the rear sides, a detachable frame forming a part of said signal case adapted to engage and lock said plurality of elements together in fixed engagement and adapted for release to permit extraction and interchange of the sectional elements.

5. In combination in an automobile signal casing, a plurality of sign panel boxes having a rectangular cross-section, a flush top side and bottom side on each box and a straight front and rear on each box, sign panels in the front and rear of each box and an enclosing frame for said casing engaging said plurality of boxes to support the same nested in rigid position and a light in each of said boxes between the front and rear sign panels.

In testimony whereof, I have signed my name to this application, this 16 day of January, 1923.

LOUIS VAN GALE.
